UNITED STATES PATENT OFFICE.

WILLIAM S. CURTIS AND EDWARD F. CURTIS, OF PORTLAND, OREGON.

DREDGE.

1,056,633.

specification of Letters Patent. Patented Mar. 18, 1913.

Application filed June 29, 1912. Serial No. 706,532.

To all whom it may concern:

Be it known that we, WILLIAM S. CURTIS and EDWARD F. CURTIS, residing at Portland, in the county of Multnomah and State 5 of Oregon, have invented certain new and useful Improvements in Dredges, of which the following is a specification.

Our invention relates to dredges and it comprehends certain improvements in the 10 construction thereof that will be herein-after fully explained specifically pointed out in the claims and illustrated in the accompanying drawings.

The primary object of our invention is the provision of certain improvements in pipe dredges of a simple but highly efficient character for gathering the earth, mud, gravel or sand, etc., mingled with water, at the bottom of a river or harbor, and forcing the 20 same, under a hydraulic pressure through a giant nozzle and discharging the gathered material at a desired distance from the original excavation without the use of pipe lines, barges, troughs, etc., such as are commonly 25 used for conveying the discharged collections from the gathering point.

Another object of our invention is the provision of certain improvements in dredges, whereby to produce the hydraulic giant 30 effect of discharging the material collected by the dredging apparatus *per se*, in such a manner as to effect a great saving in time and labor, by eliminating the handling and anchoring of pontoons, such as are commonly 35 used for supporting a pipe line discharge as well as the refitting of pipe joints in the said line.

A further object of our invention is the provision of an improved construction of 40 dredging apparatus having a special design and cooperative arrangement of parts whereby the same is capable of working advantageously in rough water as well as in smooth water.

45 Referring now to the drawings,—Figure 1, is a plan view that shows the general construction and arrangement of the parts that constitute our improved dredge. Fig. 2, is a diagrammatic side elevation thereof. Fig. 50 3, is a detail top plan view (parts being broken away) of the means for supporting and raising and lowering the suction pipe and cutter devices. Fig. 4, is a detail cross

section on the line 4—4 on Fig. 3. Fig. 5, is a detail view of the ejecting nozzle coupling. Fig. 6, is a detail perspective view of the cutter.

In the practical application of our invention, the same, in its complete make-up, includes a suitable vessel 23 in the nature of a 60 hull with a divided stern.

1 designates a rotary cutter for cooperating with the suction pipe 5 that leads to a single centrifugal pump 6, suitably mounted 65 upon the hull deck and coupled with and driven by the engine or motor 15 which is in direct connection with the said pump 5, the latter furnishing the suction power for gathering the dredged material loosened by the rotary cutter carrying shaft 27 to which 70 power is transmitted, through the gear 30 on a shaft 3 mounted on the dredging end of the hull, see Figs. 1 and 2, and which meshes with the gear 28 on the shaft 27. Suction pipe 5 includes a main or suction 75 portion that terminates in a yoke 50 including laterals 51—51 rockably mounted in the adjacent sides of the divided end of the hull and a main or offtake portion 52 that joins with a fluid-tight coupling or union 53 80 mounted on one of the pipe laterals 51, as is clearly shown in Fig. 4, by reference to which it will be also noticed that the other lateral 51, which forms one of the journals for the frame, is closed by a cap 54. The 85 offtake portion 51 of the pipe 5 conveys the dredgings to the pump 6 and from the said pump, they are drawn off into a pipe line 7 that connects with the four-way coupling 70, the laterals 71 of which are normally 90 closed by cap plates 72.

One of the outlets 72 of the coupling 70 detachably joins with a short pipe line 73 that delivers the dredging from the single stage centrifugal pump 6 to a multi-stage 95 centrifugal turbine or turbo-centrifugal pump 8 of the commercially known type, which creates a high hydraulic pressure for discharging the collected mud, earth, sand, gravel, or other solids, mingled with water 100 through the discharge pipe 9 that extends forwardly and upwardly and connects with a pipe section 90 mounted on the top of a steel trussed supporting frame or tower 11.

10 designates a giant nozzle and the same 105 has an adjustable ball and socket connection

12 with the pipe section 90, see Fig. 5, to facilitate adjusting the said giant nozzle in the directions desired.

13 and 14 designate boilers for operating the engines for the single and the multi-stage pumps 6 and 8 respectively and 16 designates an engine for operating the cutter shaft, the transmission gearing and the gearing for actuating the devices for raising and lowering the cutter and suction pipe intake portion frame 2, the bottom of which carries collar mountings 20 fixedly connected to the pipe laterals 51 to turn therewith, it being understood that the yoke end 15 50 of the suction pipe rocks in its side bearings.

17 designates a series of drums or winches mounted on a shaft geared with and driven from a countershaft 18 mounted on the hull 20 deck and geared with and driven by the crank shaft that actuates the cutter 1 and the frame 2.

19 designates steel cables that work through pulleys on the four corners of the hull for anchoring and changing the position of the hull, it being understood the said cables engage and wind on the winches 17.

20^a designates a winch that takes up a hoisting cable 21 that passes up over a pulley block 22 pendent from the upper end of a support or crane 24 fixedly mounted on and projected over the divided end of the hull. Cable 21 passes down over a pulley block 25 on a hanger 26 that includes a 35 chain sling 29 for passing around the front end of the suction pipe 5. From block 25, the cable 21 passes back over the pulley 22 and connects with the hanger 26, as shown.

While we have not illustrated it, in practice countershaft 18 is equipped with friction and clutch devices of any well known type for selecting and throwing into and out of action the desired ones of the winding winches or drums.

45 From the foregoing taken in connection

with the drawings the construction, the manner of operation and the advantages of our invention will be readily apparent.

By reason of arranging the dredging and discharging means as shown and described, 50 the said means can be readily installed on a self-propelled sea-going hull, and capable of working continuously while the said sea-going hull is in motion and since the use of pontoons and pipe lines thereto are eliminated our improved dredging means is practicable in water rougher than that in which pipe lines supported by pontoons could work. 55

What we claim is:

1. In a dredge, a hull, a frame thereon projected over one end thereof, a digger and a suction pipe section mounted thereon, a discharging nozzle mounted on the other end of the hull, a primary pumping means connected with the suction pipe, and a secondary pumping means in communication with the first pumping means and the nozzle. 60

2. In a dredge, a hull, a frame thereon projected over one end thereof, a digger and 70 a suction pipe section mounted thereon, a discharging nozzle mounted on the other end of the hull, a primary pumping means connected with the suction pipe, a secondary pumping means in communication with the 75 first pumping means and the nozzle, the said primary pumping means comprising a single stage centrifugal pump and the secondary pumping means consisting of a multi-stage centrifugal pump.

WILLIAM S. CURTIS.
